UNITED STATES PATENT OFFICE.

WESLEY G. NICHOLS, OF CHICAGO HEIGHTS, ILLINOIS, ASSIGNOR TO AMERICAN MANGANESE STEEL COMPANY, OF CHICAGO, ILLINOIS, A CORPORATION OF MAINE.

RAILROAD CROSSING WITH RENEWABLE CENTERS.

Application filed September 10, 1921. Serial No. 499,762.

To all whom it may concern:

Be it known that I, WESLEY G. NICHOLS, a citizen of the United States, residing at Chicago Heights, in the county of Cook and State of Illinois, have invented certain new and useful Improvements in Railroad Crossings with Renewable Centers, of which the following is a specification.

My invention relates to cast manganese railway crossings and has particular reference to a novel construction at the crossings, intersections or points of railways which facilitates the production and prolongs the usefulness of the structure by simplifying and insuring successful heat treatment of the crossing members, and avoiding the developments of cracks at the intersections thereof.

Practically all the major failures of cast metal crossings occur at the intersections and are due to cracks developing in the flangeways or to the "pounding down" of the points. Cracking of the flangeways has heretofore been eliminated to a material extent by increasing the metal under the intersections but this has worked against proper heat treatment, especially in manganese steel crossings. Furthermore, by employing heavier castings the shrinkage of the castings becomes more noticeable and harmful. Another objection to increasing the metal under the intersections is that it reduces resiliency at the points, and induces rapid "pounding down" of the points or cracking of the flangeways.

My invention, while preferably embodied in a crossing made in a single casting, is also applicable when desirable, to crossings made in two or more sections, suitably secured together. It consists primarily in forming the cast crossing members, at their crossing points, with recesses, and manganese steel inserts in these recesses. Preferably the overall dimensions of the inserts are made slightly less than the corresponding dimensions of the recesses, to provide clearance for slight irregularities in the cored recesses and also in the inserts themselves.

In addition to increasing the life of the crossing and at the same time simplifying and improving the manufacture of the same, the present invention provides railroad

crossings having removable crossing points which are supported on a resilient bed for absorbing shocks incident to traffic.

The various novel features of my invention will be apparent from the following specification and drawings and will be particularly pointed out in the appended claims.

In the drawings:

Figure 1 is a top plan view of a railroad crossing constructed in accordance with my invention, and made in a single casting;

Figure 2 is a plan view showing the preferred construction of removable crossing point insert;

Figure 3 is a vertical section taken on line 3—3 of Figure 2; and

Figure 4 is a section taken on line 4—4 of Figure 2.

In the preferred embodiment illustrated in the drawings in which the crossing is made as a single casting, comprising four intersections A, B, C and D, these intersections are shown as being at 90°, although this is not essential as any angularity desirable may be used. This preferred embodiment further comprises splicing extensions 5, adapted to be bolted to and co-operate with track rails (not shown). The upper portion of the casting is formed with the usual grooves 6 for the wheel flanges and the tread portions 7 for supporting the threads of the wheels and forming continuations of the track rails.

Further referring to the preferred embodiment, in casting the crossing, cavities 8 are formed by cores in the usual manner, and with such dimensions as to include the area of the crossing points. As formed, a cavity extends downwardly for considerable distance as may be observed by reference to Figure 3 of the drawings, and has a bottom 9, and sidewalls that are vertical. Inserts or blocks 10 are cast which in overall horizontal dimensions are slightly less than the corresponding overall dimensions of the cavities, but which otherwise substantially fill the cavities and restore continuity of the wheel receiving surfaces. The several sectors of the cavities and inserts are made symmetrical so that by partial rotation of an insert after excessive wear has developed on a set of rail receiving faces, in a given

position, another set may be presented to that position instead of having to replace the inserts.

On the bottom 9 of that portion of the crossing member forming the lower part of a cavity 8, I place a series of steel plates 9^a on which rests the insert 10. These plates serve two purposes. In the first place they develop a degree of vertical resiliency in the support 5 of the crossing member which greatly relieves it from the hammering shocks of passing wheels; and in the second place they serve as shims for accurately determining the level at which the wearing surface of the 10 crossing member is supported, and by the addition of a plate or plates as the wear on the upper surfaces proceeds, said plates afford means for keeping the crossing member at the proper level to avoid hammering. 15 For securing the inserts in position, they are provided with recesses 10^a in portions thereof that lie opposed to the fillets 11 between the rail stubs 12; and into the bolt 20 openings 13 and 14, formed respectively 25 through the corner walls 10^b of the recesses and through the fillets 11 of the crossing rails, are loosely fitted bolts 15 or similar securing means. In order that bolts 15 may be introduced from the outside, their shanks 30 16 are made of angular section and tapered as shown, and seated between the filling wedges 17, and the lower walls of the bolt openings 13 and 14. An advantage of this 35 method of securing the insert is that it leaves a solid sustaining foot 19 beneath the intersection of the treads and the flange grooves of the insert, as well as sustaining walls 19^a radiating from said foot in vertical planes 40 of the trackage over the insert, all of which, 45 with the perimeter walls, rest upon the bottom support provided for the insert. Such a construction prevents bodily displacement of the inserts when once in position. The plates 9^a form a spring or resilient bed for 50 the inserts so that as traffic passes over the inserts pounding is transmitted to the spring plates and absorbed, thereby eliminating breakage and unevenness at the crossing points, which is the main cause of destruction of crossing members, especially those made of cast metal.

In the solid type of crossing, especially where manganese steel is used, experience has shown that heat treatment of the solid 55 crossing has been far from uniform as some of the sections were heavy and some light, and this resulted in cracks developing in the flangeways. The construction of my crossing makes possible the successful employment of manganese steel for this work since 60 by providing cavities to receive the inserts and box like or hollow construction for the under portion of the crossing members successful heat treatment is possible, and by 65 subjecting the whole crossing member to the

proper heat treatment, it is possible to eliminate imperfections in the castings.

By forming the inserts slightly smaller than the cavities it is possible to utilize these inserts without machine grinding, which 70 would be a source of great expense especially with respect to manganese steel. It is also possible to put the inserts in the cavities without having to grind the cavities.

With inserts constructed in accordance 75 with this invention it may readily be seen that as the tread portions 20 of Figure 1 become worn to such an extent as to make uneven crossing points the insert castings may be turned to present the unused tread surfaces 80 21 to such positions. The inserts may be turned as may times as desired until all of the tread surfaces are worn to such an extent as to require replacement of the insert.

It may be observed that my invention 85 includes means for positively retaining the inserts in position in the crossing member in such manner that no displacement thereof will occur. By leaving clearance between the bolts 15 and openings 13 in the inserts, 90 vertical movement of the inserts in the crossing member permitted by the cushioning action of plates 9^a may take place without shearing the bolts.

While I have described more or less precisely the details of the preferred construction of my invention, I do not wish to be understood as limiting myself thereto, as I contemplate changes in form and in proportions of parts and substitution of equivalents 100 as circumstances may suggest or render expedient, without departing from the spirit of my invention.

I claim:

1. A railway crossing member constructed 105 with trackage directed toward a point of intersection and having around such point, a center-piece cavity, providing a bottom support, and in said cavity and resting on said bottom support, an insert piece carrying 110 upon its upper surface the intersecting portions of the trackage, and upon its lower side a central supporting foot beneath the said intersecting portions, sustaining walls radiating from said foot and perimeter walls 115 joining said radial walls; all of said walls, and said foot being extended downwardly to and resting upon the bottom support.

2. A railway crossing member constructed 120 with trackage directed toward a point of intersection and having around such point, a center-piece cavity, providing a bottom support, and in said cavity and resting on said bottom support, an insert piece carrying 125 upon its upper surface the intersecting portions of the trackage, and upon its lower side a central supporting foot beneath the said intersecting portions, sustaining walls radiating from said foot and perimeter walls 130 joining said radial walls; all of said

walls, and said foot being extended downwardly to and resting upon the bottom support; said bottom support comprising a resilient pile of thin plates.

- 5 3. A railway crossing member constructed with trackage directed toward a point of intersection and having around such point, a center-piece cavity, providing a bottom support, and in said cavity and resting on 10 said bottom support, an insert piece carrying upon its upper surface the intersecting portions of the trackage, and upon its lower side a central supporting foot beneath the said intersecting portions, sustaining walls radiating from said foot and perimeter walls joining said radial walls; said cavity having 15 a wall adjacent a perimeter wall and means being provided to resist displacement of the center-piece comprising a bolt introduced 20 from the exterior inwardly through said

cavity wall and adjacent perimeter wall and a wedge engaging the inner end of the bolt and resisting withdrawal of the bolt and displacing it downward.

4. A track crossing member formed with 25 a cavity at the crossing point, an insert in said cavity, and a resilient support in said cavity for said insert, comprising a plurality of superposed plates.

5. In a railway crossing, in combination 30 with intersecting lines of track, a block constructed to form continuations of said lines of track at the point of intersection, and releasably secured at such intersection, and a plurality of relatively thin plates located 35 beneath said block.

Signed at Chicago Heights, Illinois, this 6th day of September, 1921.

WESLEY G. NICHOLS.
